FREDERICK F. ZAVATKAY, OF WINSTED, CONNECTICUT

SPIKE SETTING DEVICE

Application filed February 5, 1932. Serial No. 591,069.

This invention relates to an improved spike setting device particularly adapted for employment in connection with the driving of railway spikes and is designed to produce a portable and efficient spike setting tool adapted for more rapidly setting of spikes, assuring a greater degree of accuracy and resulting in reduced damage to the ties during driving and to possess other advantages which contribute to obtain an improved track structure.

Important features of my improved device consist in the arrangement of a supporting member formed to provide a bearing for a hammer rod and to form a magazine and guideway for holding a supply of spikes; a conveniently actuated, escapement, supporting means for spikes within the magazine operable to allow of their being fed successively to a driving position; yieldable supporting means for the spike in driving position; resilient means operative normally but retaining the hammer rod in semi-elevated position to allow of feeding the spikes thereunder; an improved manner of supporting the device upon a rail section having provision for adjustment to different rail sections and having associated therewith improved means for more conveniently shifting the position of the device with relation to ties.

In addition to obtaining more accurate setting of the spikes, the use of my improved device eliminates the physical dangers incident to the setting of the spikes by hand, including the danger of flying spikes and likewise eliminates the loss of spikes particularly as related to trestle and bridge installation. It also offers economy by reason of the more rapid setting and avoidance of damage to the ties by improper setting.

The described and other features and advantages of my improved device will be more fully understood by reference to the accompanying drawings wherein like reference characters are applied to the corresponding parts in the several views.

In the drawings:

Figure 1 is a view in side elevation of my

improved spike setting device illustrating the manner of its use.

Figure 2 is an end elevation thereof taken from the right-hand side.

Figure 3 is a detail, longitudinal, sectional view taken centrally or on the line of separation of the frame members. 55

Figure 4 is a view in rear elevation taken from the opposite side from that of Figure 1.

Figure 5 is a horizontal sectional view 60 taken on line 5—5 of Figure 1.

Figure 6 is a detailed vertical sectional view taken in a plane transverse to the rail section.

Figure 7 is a detailed view of the escapement lever with fulcrum arrangement; and 65

Figure 8 is a detailed view of the escapement detent construction.

In the approved embodiment of the features of my invention as here illustrated, 70 the supporting and guiding frame is formed of two mated cast members 1 and 2, having a vertical and longitudinal line of separation and mutually formed to provide a guideway, circular in cross-section, for a driving rod or hammer element and also a feed channel or magazine for the spikes. As shown, each frame member is formed with a web portion 4 having their inner faces in abutting relation and formed at each marginal 80 side edge portion with a curved section 5 having a semi-circular channel 6 adapted in conjunction with the similar channel of the mated section to form a guide bearing for the hammer rod 7 which is of circular cross section. At the opposite marginal edge of the frame members they are formed to provide channels 9 and 10, the upper and major portion of which is vertical and terminating at the lower end in a curved continuation 85 toward the hammer rod guideway. The channel 9, as indicated, is of a form conforming substantially to the heel portion of the spike head of standard form and the complementary channel 10 is formed to receive freely therein the rail engaging nose portion of the spike, the grooves conjointly forming 90 a magazine for guiding and supporting the spikes which may be fed into the magazine 95

100

so formed from the upper, open, end thereof.

It is arranged that the spikes from the magazine shall be fed or advanced one at a time to a driving position beneath the hammer rod. For this purpose a suitable, manually operated, escapement support is provided which upon manipulation will release the spikes in succession to be advanced by gravity into a driving or setting position. The escapement mechanism, as shown, consists of escapement lever 12 pivotally supported at 13 upon a bracket 14 affixed to the supporting frame, the lever being formed at its upper end with a finger grip portion or handle 15 and being formed with a detent or stop shoulder 16 at its lower portion positioned to extend into the path of movement of the spikes to act as a releasable support therefor. To provide an escapement action, in conjunction with the detent 16, there is positioned in suitable relation thereto a co-acting movable detent 18, as best shown in Figures 2 and 8. The detent 18 is in the form of a stop pin having a sliding bearing in a suitably formed bracket 20 mounted upon the frame member and formed with an extension bracket 21 for the pivot pin 22 upon which is pivotally mounted a bell crank lever 23 having an upper arm positioned to be engaged by the escapement lever 12 and having its lower arm engaging the enlarged outer end 24 of the detent pin 18 whereby upon rocking of the escapement lever 12 in one direction the engagement with the bell crank lever will effect movement of the detent pin 18 in the opposite direction, the latter detent being likewise positioned to extend within the path of movement of the spikes so as to be engaged thereby when within an inner position. Within a bearing socket formed in the bracket 20, as shown, a spring 26 is fitted to underlie the enlarged head portion 24 of the detent 18 to be normally operable to move the detent into outer and spike releasing position, as shown in Figure 8.

At the upper end of the escapement lever 12, as best shown in Figure 7, it is formed with a socket portion 27 having a bearing aperture to which is fitted a spring pressed pin 28 engaged by a compression storing 29 having a rear bearing upon an adjusting screw stud 30 and normally operative to rock the escapement lever whereby its detent 16 will be moved into the path of movement of the spikes to engage the under side of a spike shank, as shown in Figures 2 and 5.

The supporting or frame member is provided at its upper portion with a bearing plate or bracket 30 forming a rest for the palm of the hand for more conveniently operating the finger grip portion 15 in the rocking of the escapement lever. The oscil-

lating or rocking movement of the escapement lever is limited in one direction by a lower stop 32 and by the engagement of the bell lever with the bracket 20 in the opposite direction. The structure in so far as described forms an escapement or releasable support for a supply of spikes positioned horizontally within the magazine, as best shown in Figures 1 and 5, with the spike shanks projecting outwardly through the guide opening formed by flanges 36 of the supporting members; the spikes being normally supported upon the detent 16 and being released to drop by gravity upon rocking of the lever at which time the detent 18 will move into the position underlying the spike next to the bottom for temporarily supporting the column as the bottom spike is released to drop by gravity. The return of the lever by the spring action will again move the detent 16 into initial supporting position, whereby upon each cycle of movement of the escapement lever the lowermost spike will be released. When so released the lowermost spike will drop by gravity through the curved portion of the magazine guide opening, the curvature of the guide opening, as will be readily understood, progressively shifting the position of the spike toward the vertical. As the spike leaves the curved guideway at its lower extremity, it is brought into a vertical or upright position beneath the hammer rod by engagement with the yieldable supporting guide member 40 pivotally supported on the frame at 41 and yieldably retained in a vertical position by means of a coil spring 42 supported on a bracket 43. The normal position of the guiding support 40 is as shown in Figure 3 in full lines with its rear wall portion in vertical position as determined by the engagement of its upper end portion 44 with a horizontal lower end surface 45 on the supporting member. In this driving or setting position the head of the spike will have a temporary bearing upon the upper end of the supporting member 40 and in the driving of the spike by means of the hammer the supporting member 40 by reason of its yieldable support will be displaced to allow the downward movement of the spike, as indicated by dotted lines in Figure 3. To allow of so feeding of the spikes by gravity and to the driving position beneath the hammer rod, the latter is normally supported to assume a semi-elevated position, as indicated in Figure 3, by means of a coil spring 46 surrounding the upper end of the hammer rod to bear at its lower end upon the supporting frame and at its upper end upon a collar 47 on the lower end of the hand grip member or sleeve 48 fixed on the hammer rod. The spring 46 accordingly operates normally to support the hammer rod in a slightly elevated position to provide for the passage of

the spikes into driving position and in the setting operation the hammer rod is raised in its guideway and allowed to descend by its weight to engage and drive the spike, compressing the spring when so doing.

To insure of the proper positioning of the spike in the driving position, the escapement lever 12 at its lower end is formed with a curved extension 50 having a shoulder 51 extended into the path of movement of the spike and adapted to engage the side of the spike opposite to the engagement with the guide member 40 so as to co-act therewith in retaining the spike in upright position. The shoulder 51 as will be understood will be movable upon rocking of the escapement lever out of spike engaging position when the lower end of the lever is rocked outwardly to allow feeding of the spike.

Further improvements which contribute to the more successful operation of the present device include an improved adjustable supporting means for the frame member adapted to have bearing support upon the rail so as to be adjustable in relation thereto to adapt the device for properly setting the spikes in relation to different rail sections. The improved supporting or rail bearing means as here shown comprises an angular bracket member 54 having a lower horizontal flange 55 for bearing rest upon the rail head and a vertical portion having a vertical key enlargement 56 fitted within a guideway or groove 57 formed in the frame member 2 so as to be adjustable vertically with relation thereto to determine the height with relation to a particular rail section. The bracket member 54 is formed with a vertical slot 58 through which is passed a screw stud 59 secured to the frame member 2 and upon which is threaded a clamping nut 60 having a lever extension 61 for conveniently clamping the bearing support 54 to the frame member. For determining the correct horizontal relation of the spike to the rail base flange, a roller support and guide plate 62 is adjustably secured on the flange member 55 of the bearing bracket 54 and is formed as shown with bearing portions 63 extended longitudinally of the rail at the opposite sides of the frame and within which are journaled suitable rollers 64 having guide flanges 65. The plate 62 is secured upon the bracket 54 by means of a screw stud 66 and clamping nut 67, the stud being received in an elongated slot in the plate 62 which is likewise provided with a second elongated slot to receive a retaining stud 68 carried on the flange 55. This arrangement accordingly allows of horizontally adjusting of the guide plate 62 with relation to the frame member of the device to determine the proper horizontal relation of the spike to different rail sections. In further accordance with the invention the guide

plate 62 is desirably formed whereby with the frame in vertical position, the guide rollers 64 are spaced slightly above the top of the rail head so that when in operating position a firm bearing rest is had upon the rail section and when it is desired to shift the position of the device to another tie it may easily be effected by a slight tilting to shift the support upon the rollers in one direction or the other.

For convenience in handling, the frame members are provided with hand grips 70 and 71 and, as best shown in Figure 6, a finger set screw 72 is threaded to one of the frame members to engage with the hammer rod for locking the rod from movement when desired, as for instance during transportation.

Having described my invention, I claim:

1. A spike setting device of the character described comprising a frame member formed with a hammer rod bearing and with a magazine guideway adapted to receive spikes therein, said guideway being of curved form at its lower end portion for guiding the spikes to a driving position beneath the hammer bearing, yieldable means adapted to support the spikes in position for driving, a hammer rod fitted to the bearing, resilient means normally operative to support the hammer rod to allow feeding of the spikes thereunder, a manually operable escapement means positioned to support the spikes and to successively release the spikes to descend into driving position.

2. A spike setting device of the character described comprising a supporting frame having bearing for a hammer rod, a hammer rod fitted to reciprocate in said bearing, said frame being provided with a magazine guideway for the spikes adapted to guide the spikes to a position beneath the hammer rod, escapement means to control the feed of the spikes and resilient means normally to support the hammer rod in position to allow the feeding of the spikes thereunder.

3. A spike setting device of the character described comprising a frame provided with a hammer rod bearing and means for guiding the spikes to a driving position thereunder and supporting means for the frame consisting of a bearing member adjustably secured to the frame and adapted for bearing support upon a rail.

4. A spike setting device of the character described comprising a frame provided with a hammer rod bearing, a hammer rod within the bearing, means for guiding the spikes to a driving position thereunder, supporting means for the frame consisting of a bearing member adjustably secured to the frame and adapted for bearing support upon a rail and a supplemental bearing member secured thereto and provided with roller means

adapted to bear upon the rail upon tilting of the frame.

5. A spike setting device of the character described comprising a frame provided with a hammer rod bearing, a hammer rod within the bearing, means for guiding the spikes to a driving position thereunder, supporting means for the frame consisting of a bearing member adjustably secured to the frame and 10 adapted for bearing support upon a rail and a supplemental bearing member secured thereto to be adjustable laterally of the rail and provided at each end with journalled rollers positioned to be normally spaced from 15 the rail and to bear upon the rail upon tilting of the frame.

6. A spike setting device of the character described comprising a frame provided with a hammer rod bearing, yieldable means 20 adapted to support the spikes in position for driving, a hammer rod fitted to the bearing, resilient means normally operative to support the hammer rod to allow of feeding the spikes thereunder and means for guiding the spikes 25 to driving position.

7. A spike setting device of the character described comprising a frame member formed with a hammer rod bearing and with a magazine guideway adapted to receive 30 spikes therein, said guideway being of curved form at its lower end portion for guiding the spikes to a driving position beneath the hammer bearing, yieldable means adapted to support the spikes in position for 35 driving, a hammer rod fitted to the bearing, resilient means normally operative to support the hammer rod to allow feeding of the spikes thereunder, manually operable escapement means adapted to support the spikes in 40 the guideway consisting of a pivotally supported escapement lever provided with a detent movable into the path of the spikes to support the latter, a co-acting movable detent actuated by the lever for supporting the 45 uppermost spikes upon the withdrawal of said first detent to release the lowermost spike.

8. In a device of the character described 50 comprising a supporting and guiding frame formed with a hammer rod bearing and a magazine guideway for the spikes, said guideway being formed for guiding the spikes to a driving position beneath said bearing, a hammer rod positioned within the 55

bearing and manually operable escapement means associated with the magazine guideway consisting of a pivotally supported escapement lever provided with a detent movable into the path of the spikes to support the latter, a co-acting movable detent actuated by the escapement lever for supporting the uppermost spikes upon withdrawal of said first detent to release the lowermost spike, substantially as described.

9. In a device of the character described comprising a supporting and guiding frame formed with a hammer rod bearing and a magazine guideway for spikes, said guideway being formed for guiding the spikes to a driving position beneath the rod bearing, a yieldable supporting and guiding means for the spikes positioned beneath the hammer rod bearing, a hammer rod positioned within the bearing and manually operable escapement means associated with the magazine guideway consisting of a pivotally supported escapement lever provided with a detent movable into the guideway for supporting the spikes, a co-acting movable detent actuated by the escapement lever for supporting the uppermost spikes upon withdrawal of said first detent to release the lowermost spike and said escapement lever being provided with a lower extension provided with a shoulder positioned to co-act with the yieldable guiding means for retaining the spike in driving position.

10. A spike setting device of the character described, comprising a frame member composed of complementally mated sections formed to provide a vertical hammer rod bearing and a marginally disposed open sided magazine guideway formed to receive the head portions of the spikes, said guideway being of curved form at its lower portion for guiding the spikes to a driving position beneath the hammer bearing, means to secure the frame sections, yieldable means for supporting the spikes in position for driving, a hammer rod fitted to the bearing and manually operable escapement means positioned to support the spikes in the guideway and operable to successively release the spikes to descend into driving position.

Signed at Winsted in the county of Litchfield and State of Connecticut this 23rd day of March A. D. 1931.

FREDERICK F. ZAVATKAY.
